UNITED STATES PATENT OFFICE.

JOHN C. MCCOLGAN, OF PORTLAND, OREGON.

WOOD-SPLITTING DEVICE.

Application filed April 14, 1924. Serial No. 706,555.

The present invention relates to a wood splitting device and has for its principal object to provide a pneumatic operating mechanism for efficiently operating the same.

Another important object of the invention is to provide a device of this nature possessed of a comparatively simple and efficient construction, one which is reliable in operation, durable, strong, and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing:

Figure 1 is a longitudinal section through the device embodying my invention showing the same in its normal contracted position,

Figure 2 is a similar section showing the same almost fully extended,

Figures 3, 4 and 5 are transverse sections taken on the lines 3-3, 4-4 and 5-5 respectively of Figure 1, looking in the direction of the respective arrows.

Figure 6 is a detail view showing the structure of the wedging element itself,

Fig. 7 is a section on line 7-7 of Fig. 1 and

Fig. 8 is a section on line 8-8 of Fig. 1.

Referring to the drawing in detail it will be seen that the wedging element indicated generally at A comprises a wedge shaped body 1 having an elongated tip 2, the body 1 and tip 2 both being provided with upwardly pitched teeth 4 on each side thereof so that the wedging element will be difficult of removal from wood after the same has been engaged and is being pushed therein.

The operating mechanism for this wedging element consists of an inner cylinder 5 and an outer cylinder 6 telescopically associated with each other. The inner cylinder 5 is extended slightly into the body 1 of the wedging element A and fixed thereto by means of a pin 7. The larger end of the body 1 is provided with a buffer ring 8 against which the outer cylinder 6 is adapted to strike, the lower end of the cylinder 6 being enlarged as at 9 so as to engage the inner cylinder, the remaining portion of the outer cylinder being spaced from the inner cylinder as is shown in both Figures 1 and

2. When the cylinders are in a contracted position as shown in Figure 1 the cylinder 6 extends above the cylinder 5. The upper end of the cylinder 6 is closed by an apertured plate 10 through which extends the pipe 11 leading from some source of compressed air or the like. The inner end of this pipe 11 is provided with a piston 12 having openings 28 and the cylinder 6 is adapted to slide thereon. A disk 13 is mounted within the cylinder 6 above the cylinder 5 and pins 14 project therefrom through the piston 12. This disk 13 is slidable on the brackets 16 which are attached to the piston 12 and also to the upper end of cylinder 5. These brackets 16 are grooved as is indicated to advantage at 16' in Figure 5 so that the air may pass through the grooves 16' and through the disk 13 as well as around its ends. A valve 17 is mounted in the upper end of the cylinder 6 for association with the closure 10 the latter having apertures 10'. This valve is normally held spaced from the closure 10 by springs 18 embedded in the closure and impinging against the valve. A U-shaped member 19 is attached to the valve 17 and the legs thereof extend movably through the piston 12 and the disk 13, the intermediate portion 20 of the U-shaped member being disposed within the cylinder 5 intermediate its ends when the cylinders 5 and 6 are contracted but this intermediate portion moves out of the cylinder 5 when the two cylinders are extended as will be noted by an inspection of Figures 1 and 2. A rod 23 is fixed centrally to the disk 13 and depends into the cylinder 5 terminating in a piston 24 movable within cylinder 5 and normally resting on a pin 25 extending transversely of the cylinder 5 adjacent its bottom end. When the valve 26 of the line or pipe 13 is open the operator presses downwardly upon the cylinder 6 to hold the wedging elements against an object and the air flows into the two cylinders filling the spaces therein causing valve 17 to close against the closure 10. When the operator presses downwardly upon the cylinder 6 the springs 18 and 27 are compressed so that the pins 14 force the valve 17 in abutment with the closure 10 thereby closing its openings 10'. The air will flow through the pipe 11 filling the two cylinders 5 and 6, it being noted that the air is free to pass through the piston 12 because of its opening 28 and through the disk 13 be-

cause of the grooves 16' in the bracket 16. As the air is compressed within the cylinder 5 the piston 24 tends to move downwardly thereby holding the disk 13 in place. This causes the cylinders to move in relation to each other taking the position shown in Figure 2 at which time the intermediate portion 20 of the U-shaped member 19 has engaged the disk 13 so as to bring the same 10 in abutment with the piston 12 and as the cylinders further expand it will be seen that this U-shaped member will open the exhaust valve 17 thus relieving the pressure in the device and the weight of the cylinder 6 will 15 cause the same to fall or move downwardly so as to strike against the wedging element. As the outer cylinder strikes against the wedging element the disk 13 engages buffer spring 27 on the cylinder 5 so that the pins 20 14 engage the exhaust valve and force the same closed and thus the operation will be repeated.

It is thought that the construction and operation of the invention should now be 25 clearly understood without any more detail description thereof. It is desired, however, to point out that numerous changes in the details of construction, and in the combination and arrangement of parts may be resorted to without departing from the spirit or scope of the invention as hereinafter claimed.

Having thus described my invention, what I claim as new is:

35 1. A device of the class described including an inner cylinder and an outer cylinder slidable thereover, an apertured closure on the upper end of the cylinder, a valve associated with the closure, an air pipe leading through the closure and terminating in a piston within the outer cylinder on which said outer cylinder is slidable, a disk within the outer cylinder below the piston, pins extending from the disk through the piston, a U-shaped member depending from the valve through the piston and disk so as to hold the disk against the piston and open 40 the valve when the cylinders are extended, said pins being adapted to force the valve to a closed position when the disk abuts the top of the inner cylinder when said cylinders are in a contracted position, and buffer 45 springs mounted on the end of the inner cylinder engaged with said disk strikes.

to a closed position when the disk abuts the 50 top of the inner cylinder when said cylinders are in a contracted position.

2. A device of the class described including an inner cylinder and an outer cylinder slidable thereover, an apertured closure on 55 the upper end of the cylinder, a valve associated with the closure, an air pipe leading through the closure and terminating in a piston within the outer cylinder on which said outer cylinder is slidable, a disk within 60 the outer cylinder below the piston, pins extending from the disk through the piston, a U-shaped member depending from the valve through the piston and disk so as to hold the disk against the piston and open the 65 valve when the cylinders are extended, said pins being adapted to force the valve to a closed position when the disk abuts the top of the inner cylinder when said cylinders are in a contracted position, and buffer 70 springs mounted on the end of the inner cylinder engaged with said disk strikes.

3. A device of the class described including an inner cylinder and an outer cylinder slidable thereover, an apertured closure on 75 the upper end of the cylinder, a valve associated with the closure, an air pipe leading through the closure and terminating in a piston within the outer cylinder on which said outer cylinder is slidable, a disk within 80 the outer cylinder below the piston, pins extending from the disk through the piston, a U-shaped member depending from the valve through the piston and disk so as to hold the disk against the piston and open 85 the valve when the cylinders are extended, said pins being adapted to force the valve to a closed position when the disk abuts the top of the inner cylinder when said cylinders are in a contracted position, and buffer 90 springs mounted on the end of the inner cylinder engaged with said disk strikes, a second piston in the inner cylinder, a rod connecting the second piston with the disk.

In testimony whereof I affix my signature.

JOHN C. McCOLGAN.
